PLANFILE CONSTRUCTION

Charles B. Ulrich, Jamestown, N. Y.

Application December 30, 1940, Serial No. 372,323

20 Claims. (Cl. 129—16)

The invention pertains to planfiles used to file in classified, vertical arrangement, large drawings and tracings as well as other papers, in flexible pockets suspended on parallel cross bars extending across the upper portion of the planfile, suitable compression devices such as helico-spiral springs, being employed between and pressing against the pockets, to compress them when not manually opened, as much as the filed contents of each pocket will permit.

Heretofore planfiles of the kind referred to, have presented two problems, first, if the compression means between the pockets were sufficiently forcible to so positively hold the walls of a pocket towards each other with but few papers or tracings in the pocket, as to prevent slippage of the papers or tracings downwardly in the pocket, difficulty was experienced in opening the upper edge portion of the pocket to inset and remove filed sheets, particularly where the supporting cross bars were free to assume positions vertically over the walls of the pocket, as has frequently been the case; and second, where the force of the compression means was made light enough to permit the ready opening manually of the upper edge of a pocket, particularly with but few papers or tracings in the pocket, the force of compression was not sufficient to hold the papers or tracings against slippage and prevent their bunching in the lower part of the pocket.

It is an object of my invention, to provide a planfile of the kind referred to, with a casing having a hinged cover and to further provide automatic devices positively opening the upper edge portions of all of the suspended pockets when the cover is raised, thereby permitting ready access to any desired pocket even though the force of the compression means between the pockets may be relatively large, and quite as positively closing and compressing the upper edge portions of all of the pockets when the cover is lowered to its casing closing position.

More specifically, it is a further object of my invention to provide operating members connected with alternate ones of said cross bars, so that movement of said operating members will move said alternate cross bars respectively towards or from cooperating intermediate ones of said cross bars to close or open the corresponding pockets, and to connect said operating members with the casing cover in such a manner that opening the cover will move the operating members to open the upper edge portions of the pockets, and closing the cover will move the oper-

ating members to close the upper edge portions of the pockets and hold them closed with any desired pressure. By this means, the compression means or springs between the pockets may be made as stiff as required to effect efficient compression of the pockets, and yet the upper portions of the pockets will be positively opened when the casing cover is opened.

The above and other objects of my invention will more clearly appear by reference to the accompanying drawings illustrating a preferred embodiment thereof, in which

Fig. 1 illustrates my improved planfile in vertical, sectional view taken from the front to rear thereof.

Fig. 2 is a vertical, sectional view to an enlarged scale of a part of the structure taken along the line 2—2 in Fig. 1.

Figs. 3, 4 and 5 are vertical sectional views of parts of the structure to a scale smaller than that of Fig. 2 but larger than that of Fig. 1, these views being taken respectively along lines 3—3, 4—4 and 5—5 in Fig. 2.

Figs. 6 and 7 are schematic views to a smaller scale than and taken in the same direction as Fig. 1, and respectively illustrate the casing cover in its opened and closed positions, and the positions thereby given to the movable ones of the pocket-suspending cross bars.

Figs. 8 and 9 show in views respectively similar to Figs. 6 and 7, a modified arrangement of the cross bar operating mechanism, and

Fig. 10 is a detail view of a part of the construction of Figs. 8 and 9.

Similar numerals refer to similar parts throughout the several views.

As shown in Fig. 1, my planfile is provided with a casing 10 having a hinged cover 11 provided with a latch bar 12 of any desired construction for holding the cover in its raised position. The side walls of the casing support in parallel arrangement, alternate cross bars 13, 13 and intermediate cross bars 14, 14, the cross bars 13 being supported for easy movement forwardly and rearwardly by rollers 15. Each of the cross bars 13 and the next adjacent cross bar 14 to the rear therefrom, support the front and rear walls 16a and 16b respectively of a flexible pocket 16 suspended from said cross bars, said walls being secured together at their lower edges by a flexible and yieldable member 16c of fabric or the like, permitting the pocket to expand and compress according to the quantity of filed material therein. The members 16c preferably support folders 17 to receive the filed contents, and each of the

walls 16b has secured thereto a downwardly extending plate 16d, which is connected below the members 16c with a pocket spacing strip 18, which strip is free from connection excepting with the pockets as stated. Compression springs 19 are provided between the pockets and between the front and rear casing walls and the adjacent pockets, to compress the pockets to the extent the contents thereof will permit, said springs being preferably of sufficient strength to hold even a few sheets of drawings or tracings in any pocket, against slippage downwardly in the pocket, even if all of the other pockets are empty.

The ends of the cross bars 14 preferably have fixed supports, whereas similar ends of the cross bars 13 are movable forwardly and rearwardly of the casing in definitely spaced relation, by a link 20 pivotally connected with an arm 21 rigidly secured to the cover 11, all as more fully described below.

As shown in Fig. 2, the upper portion of each side wall of the casing 10 has secured between and to its walls a reinforcing and supporting horizontal channel member 22, extending from the front wall to the rear wall of the casing. Adjacent the inner wall of the side wall, the channel member 22 supports a horizontal channel-shaped runway 23 with its flanges extending upwardly and extending from the front wall to the back wall of the casing, to support the rollers 15 for rolling movement therein forwardly and rearwardly of the casing. The end portion of each cross bar 13 is shouldered adjacent the end of the roller 15 which is near the inner wall of the side wall, said end portion being of reduced diameter through the roller and extended therefrom beyond the channel member 23, to and through a spacing and operating member 24 adjacent the outer surface of the runway 23, the member 24 being held in place on the end portions of the cross bars 13 by an upwardly extending flange 25a on a channel shaped member 25 reinforcing the upper portion of the casing side wall and having a second flange 25b to which a plate 26 is removably secured above the cross bars 13 and 14 to complete the inner wall of the side wall and when removed by releasing the retaining screws indicated, to afford a suitable clearance opening into the side wall to facilitate assembling the parts. The bottom portions of the flanges of the runway 23 are so spaced as to give free mechanical clearance to the roller 15 axially, but insufficiently to afford appreciable axial play to the rollers. The upper portions of said flanges are formed outwardly away from each other to reduce to a minimum the area of end engagement of each roller 15 with the runway 23. The flange 25a is spaced from the runway 23 by an amount only sufficiently greater than the thickness of the operating member 24 to permit said member to move freely longitudinally, thereby retaining said member in operative position on the ends of the cross bars 13. The inner flange 23a of the runway 23 is extended upwardly between the movable cross bars 13, and provided with upwardly opening notches engaging and fitting grooves 14b formed in the cross bars 14 closely adjacent their ends. The thickness of each end flange on each of the cross bars 14, is substantially less than the spacing of the upper portion of the flange 23a from the adjacent ends of the rollers 15, thereby permitting the rollers

15 to overlap the ends of the cross bars 14 during the operation of the device.

As also shown in Fig. 2, the operating member 24 has rigidly secured thereto, an outwardly extending stud 27, which is shouldered outside of the plane of the ends of the cross bars 13, to engage the adjacent end of the link bar 20, outside of which the stud is grooved to engage the end of a helical tension spring 28, as more clearly shown in Fig. 3.

As also shown in Fig. 2, the lower edge of the plate 26 is disposed just above and clearing the cross bars 13 and 14, thereby affording free movement to the cross bars 13, but sufficiently close to the cross bars 14 to prevent their removal from their supporting slots in the flange 23a.

The structure described in connection with Fig. 2, is duplicated in reverse arrangement in the other side wall of the casing 10, as a result of 20 which the parts are held against displacement from the relationships described, unless the plates 26 are removed.

Each of the cross bars 13 and 14 has secured thereto in any suitable manner, the upper end of 25 each of a plurality of pocket members 16e of thin sheet metal, as shown for one of said members in Fig. 2, the number per cross bar depending on the length of the cross bar and the width of the planfile, and being sufficient in any case to positively support the folders 17 employed. Each 30 pocket member 16e on one of the cross bars 13 is connected with the similar pocket member on an adjacent cross bar 14, by a flexible bottom member 16c and the pairs of pocket members so 35 connected, together constitute the pocket supported by said two cross bars.

In Fig. 3, the relation of the operating member 24 to the ends of the cross bars 13 is more clearly shown, as well as the relation of the operating 40 member to the link bar 20. It will be noted that the link bar 20 is slotted at 20a to be a sliding fit on the outer end portion of the stud 27, and that the end of the spring 28 not in engagement with the stud 27 as described, is secured to the 45 link bar 20, for example, by a screw 26b, to hold the stud 27 against the left hand end of the slot 20a (as seen in Fig. 3), with a force equal to the tension of the spring 28. As a result, when the cover 11 is closed, thereby moving the link bar 50 20, and through the spring 28 the operating member 24 to the left (as seen in Fig. 3), the cross bars 13 move from the open condition of the pockets to their closed condition (illustrated respectively in Figs. 6 and 7), until the cross bars 55 13 engage the supporting lugs 23b for the cross bars 14 (Fig. 5), or until the closing movement is stopped by reason of a full pocket or pockets, or otherwise, and continued movement of the cover 11 to its closed position holds the cross bars 13 in 60 their pocket-closing position, with the force exerted by the spring 28, the stud 27 moving sufficiently in the slot 20a to permit the completion of the closing movement of the cover 11.

Fig. 4 more clearly shows the relation of the 65 cross bars 13 to the cross bars 14 for the open condition of the pockets.

Fig. 5 more clearly shows the manner in which the cross bars 14 are supported by the flange 23a of the runway 23, and the lugs 23b adjacent the 70 slots supporting said cross bars. It will be noted that with the pockets empty or nearly so, the lugs 23b limit the movement of the cross bars 13 in closing the pockets.

In Figs. 6 and 7 illustrating schematically the 75 relation of the cross bars 13 and 14 to each other

for the opened and closed conditions of the upper edge portions of the pockets 16, and respectively for the opened and closed positions of the cover 11, it will be noticed that the length of the arm 21 placing its pivotal connection with the link bar 20 well below a straight line through the cover hinge and the stud 27 when the cover is closed, results in moving the operating member 24 towards the front of the casing 10, when the cover is moved to its open position. For this arrangement, the fixed upper edge of each pocket is to the rear of its upper movable edge. In Figs. 8 and 9 I illustrate schematically in views similar respectively to Figs. 6 and 7, a modified arrangement of the same parts as before, by which the fixed upper edge of each pocket is towards the front of the casing 10 and the movable upper edge of the pocket is to the rear of its fixed upper edge, the front pocket having its fixed cross bar resting tightly against the inner surface of the front wall of the casing 10. This arrangement has the advantage that papers cannot be accidentally slipped into the casing at any time, between the front pocket and the front wall of the casing, the main disadvantage being that the links operating the movable cross bars are more in evidence than with the construction illustrated in Figs. 6 and 7.

In the arrangement of Figs. 8 and 9, the cross bars 14a are the same as the cross bars 14 and supported in the same manner, excepting that they support the front edges of the pockets respectively. The cross bars 13a are the same and are supported in the same manner and are operated in the same way as the cross bars 13, excepting that they support the rear upper edges respectively of the pockets, and that they move towards the front of the casing to close the pockets when the casing cover 11 is closed. The operating member 24a is the same as the operating member 24, and operates the cross bars 13a in the same manner as the cross bars 13 are operated. The arm 21a, however, is substantially different and differently located from the arm 21. The arm 21a is as short as good connection with the link bar 40 will permit, and it is located substantially farther from the cover hinge than is the arm 21. The link bar 40 connecting the arm 21a with the operating member 24a is similar to the link bar 20, excepting that in closing the pockets by closing the cover 11, it is subjected to a compressive force, instead of a tensional force as exerted on the link bar 20. This results in a construction of the forward end of the link bar 40 different from that of the link bar 20, as illustrated in Fig. 10. As there shown, the forward end of the link bar 40 is provided with a longitudinal slot 40a to receive a stud 27a secured to the operating member 24a, and said link bar is continued forwardly beyond said slot a sufficient distance to support one end of a helical spring 28a, for example, by a screw 40b, the other end of said spring engaging the stud 27a, so that the spring 28a acts in quite the same manner and for the same reasons as does the spring 28.

From the above it will be seen that the planfile of my invention provides for the use of any necessary pressure of the compression springs 19, and at the same time gives ready and easy access to all of the filing pockets regardless of that pressure, and that it positively closes the upper portions of the pockets when the casing is closed, thereby preventing downward slippage of the contents of the pockets.

While I have shown my invention in the par-

ticular embodiment described, I do not limit myself thereto, as I may employ equivalents thereof without departing from the scope of the appended claims.

5. What I claim is:

1. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, and devices connecting said connecting means with said cover in such a manner that opening said cover opens the upper portions of said pockets.

2. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, and devices connecting said connecting means with said cover in such a manner that opening said cover opens the upper portions of said pockets and closing said cover closes the upper portions of said pockets.

3. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cover in such a manner that opening said cover opens the upper portions of said pockets, rollers supporting the ends of said intermediate cross bars, and channel-shaped runways supporting said rollers and restraining them against substantial axial movement.

4. In a planfile, the combination of a casing having side walls and a hinged cover, parallel and horizontal cross bars extending from side to side of the casing and in the upper portion thereof, alternate ones of said cross bars having fixed

end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cover in such a manner that opening said cover opens the upper portions of said pockets, rollers supporting the ends of said intermediate cross bars, and channel-shaped runways supporting said rollers and restraining them against substantial axial movement, the inner flanges of said runways having upwardly opening slots supporting the ends of said alternate cross bars.

5. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cover in such a manner that opening said cover opens the upper portions of said pockets, rollers supporting the ends of said intermediate cross bars, and channel-shaped runways supporting said rollers and restraining them against substantial axial movement, the inner flanges of said runways having upwardly opening slots supporting the ends of said alternate cross bars, said alternate cross bars having circumferential grooves adjacent their ends and engaging the edges of said slots and restraining said alternate cross bars from longitudinal movement.

6. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cover in such a manner that opening said cover opens the upper portions of said pockets, rollers supporting the ends of said intermediate cross bars, and channel-shaped runways supporting said rollers and restraining them against substantial axial movement, the inner flanges of said runways

75 having upwardly opening slots supporting the ends of said alternate cross bars, said alternate cross bars having circumferential grooves adjacent their ends and engaging the edges of said slots and restraining said alternate cross bars from longitudinal movement, the length of each of said alternate cross bars being less than the distance between the rollers on each of said intermediate cross bars, whereby the rollers on an intermediate cross bar may overlap the ends of an adjacent one of said alternate cross bars.

7. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, and devices connecting said connecting means with said cover in such a manner that opening said cover opens the upper portions of said pockets, said connecting means comprising a spacing and operating member parallel with each side wall of the casing and having clearance apertures therethrough in line with and containing the corresponding end portions of the intermediate cross bars.

8. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and toward and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, and devices connecting said connecting means with said cover in such a manner that opening said cover opens the upper portions of said pockets, said connecting means comprising a spacing and operating member parallel with each side wall of the casing and having clearance apertures therethrough in line with and containing the corresponding end portions of the intermediate cross bars, and said connecting devices including a pair of link bars each pivotally connected at one of its ends with one of said spacing and operating members and extending to and pivotally connected with said cover.

9. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively be-

tween said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, and devices connecting said connecting means with said cover in such a manner that opening said cover opens the upper portions of said pockets, said connecting means comprising a spacing and operating member parallel with each side wall of the casing and having clearance apertures therethrough in line with and containing the corresponding end portions of the intermediate cross bars, and said connecting devices including a pair of link bars each pivotally connected at one of its ends with one of said spacing and operating members and extending to and pivotally connected with said cover, each of said link bars having a yielding spring-connection with the corresponding spacing and operating member in the direction of the pocket-closing movement of said link bar, whereby the pocket-closing movement of said link bars may be greater than the corresponding movement of said intermediate cross bars.

10. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting 30 said connecting means with said cover in such a manner that opening said cover opens the upper portions of said pockets, rollers supporting the ends of said intermediate cross bars, and channel-shaped runways supporting said rollers and restraining them against substantial axial movement, said connecting means comprising a spacing and operating member parallel with each side wall of the casing and having clearance apertures therethrough in line with and containing the corresponding end portions of the intermediate cross bars.

11. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cov-

er in such a manner that opening said cover opens the upper portions of said pockets, rollers supporting the ends of said intermediate cross bars, and channel-shaped runways supporting said rollers and restraining them against substantial axial movement, said connecting means comprising a spacing and operating member parallel with each side wall of the casing and having clearance apertures therethrough in line with and containing the corresponding end portions of the intermediate cross bars, and said connecting devices including a pair of link bars each pivotally connected at one of its ends with one of said spacing and operating members and extending to and pivotally connected with said cover.

12. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cover in such a manner that opening said cover opens the upper portions of said pockets, rollers supporting the ends of said intermediate cross bars, and channel-shaped runways supporting said rollers and restraining them against substantial axial movement, said connecting means comprising a spacing and operating member parallel with each side wall of the casing and having clearance apertures therethrough in line with and containing the corresponding end portions of the intermediate cross bars, and said connecting devices including a pair of link bars each pivotally connected at one of its ends with one of said spacing and operating members and extending to and pivotally connected with said cover, each of said link bars having a yielding spring-connection with the corresponding spacing and operating member in the direction of the pocket-closing movement of said link bar, whereby the pocket-closing movement of said link bars may be greater than the corresponding movement of said intermediate cross bars.

13. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cover in such a manner that opening said

cover opens the upper portions of said pockets, rollers supporting the ends of said intermediate cross bars, channel-shaped runways supporting said rollers and restraining them against substantial axial movement, said connecting means comprising a spacing and operating member parallel with each side wall of the casing and having clearance apertures therethrough in line with and containing the corresponding end portions of the intermediate cross bars, and a flange member holding each of said spacing and operating members on the corresponding end portions of the intermediate cross bars and for longitudinal movement adjacent the corresponding channel-shaped runway.

14. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cover in such a manner that opening said cover opens the upper portions of said pockets, rollers supporting the ends of said intermediate cross bars, and channel-shaped runways supporting said rollers and restraining them against substantial axial movement, said connecting means comprising a spacing and operating member parallel with each side wall of the casing and having clearance apertures therethrough in line with and containing the corresponding end portions of the intermediate cross bars, said intermediate cross bars being shouldered at the inner ends of said rollers and of reduced diameter through said rollers and said spacing and operating members, thereby restraining said intermediate cross bars against substantial longitudinal movement.

15. In a planfile, the combination of a casing having side walls and a hinged cover, parallel and horizontal cross bars extending from side to side of the casing and in the upper portion thereof, alternate ones of said cross bars having fixed end supports spaced from each other amounts determining pocket openings and intermediate ones of said cross bars being mounted at their end portions for movement respectively between said fixed cross bars and towards and from the front of said casing, filing pockets suspended from said cross bars and each supported at one of its upper edges by one of said fixed cross bars and at its other upper edge by the next and a movable one of said cross bars, means connecting the end portions of said movable cross bars for simultaneous movement, devices connecting said connecting means with said cover in such a manner that opening said cover opens the upper portions of said pockets, rollers supporting the ends of said intermediate cross bars, and channel-shaped runways supporting

said rollers and restraining them against substantial axial movement, said intermediate cross bars being shouldered at the inner ends of said rollers and of reduced diameter through said rollers, thereby restraining said intermediate cross bars against substantial longitudinal movement.

16. In a planfile, the combination of a casing having a hinged cover, pocket supporting cross bars in said casing in two groups, one of said groups being fixed and the other of said groups being movable, means connecting said movable cross bars for simultaneous movement, and devices connecting said connecting means with said cover to move said movable cross bars by movement of said cover.

17. In a planfile, the combination of a casing having a hinged cover, pocket supporting cross bars in said casing in two groups, one of said groups being fixed and the other of said groups being movable, means connecting said movable cross bars for simultaneous movement, and devices connecting said connecting means with said cover to move said movable cross bars by movement of said cover, said connecting devices having positive operating connections for one direction of movement of said cover and having resiliently yielding operating connections for the other direction of movement of said cover.

18. In a planfile, the combination of a casing having a hinged cover, pocket supporting cross bars in said casing in two groups, one of said groups being fixed and the other of said groups being movable, means connecting said movable cross bars for simultaneous movement, and devices connecting said connecting means with said cover to move said movable cross bars by movement of said cover, said connecting means comprising spacing and operating members on the end portions of said movable cross bars.

19. In a planfile, the combination of a casing having a hinged cover, pocket supporting cross bars in said casing in two groups, one of said groups being fixed and the other of said groups being movable, means connecting said movable cross bars for simultaneous movement, and devices connecting said connecting means with said cover to move said movable cross bars by movement of said cover, said connecting means comprising spacing and operating members on the end portions of said movable cross bars, and said connecting devices including link bars pivotally connecting said spacing and operating members with said cover.

20. In a planfile, the combination of a casing having a hinged cover, pocket supporting cross bars in said casing in two groups, one of said groups being fixed and the other of said groups being movable, means connecting said movable cross bars for simultaneous movement, and devices connecting said connecting means with said cover to move said movable cross bars by means of said cover, said connecting means comprising spacing and operating members on the end portions of said movable cross bars, and said connecting devices including link bars pivotally connecting said spacing and operating members with said cover, said link bars having resiliently yielding operating connections in the direction of movement produced by closing said cover.

CHARLES B. ULRICH.
